INVENTOR

OTTIN OLSON.

BY *Paul & Hawley*
HIS ATTORNEYS

UNITED STATES PATENT OFFICE.

OTTIN OLSON, OF MINNEAPOLIS, MINNESOTA.

GRATE-BAR.

SPECIFICATION forming part of Letters Patent No. 659,451, dated October 9, 1900.

Application filed January 12, 1900. Serial No. 1,984. (No model.)

To all whom it may concern:

Be it known that I, OTTIN OLSON, of Minneapolis, Hennepin county, Minnesota, have invented certain new and useful Improvements in Grate-Bars, of which the following is a specification.

My invention relates to grate-bars designed especially for use in furnaces where sawdust, shavings, edgings, or slabs are used for fuel; and one object of the invention is to prevent the cracking or breaking of the bars from unequal expansion or contraction.

A further object is to provide a grate-bar made up of several parts or pieces which when broken can be easily replaced and being cast separately can be readily assembled.

The invention consists generally in a grate-bar having parallel webs or ribs and transverse fire-bars removably arranged thereon.

Further, the invention consists in various constructions and combinations, all as hereinafter described, and particularly pointed out in the claims.

In the accompanying drawings, forming part of this specification, Figure 1 is a plan view of a grate-bar embodying my invention with the fire-bars removed. Fig. 2 is a side elevation of the same. Fig. 3 is a partial plan view showing the fire-bars in position. Figs. 4 and 5 are similar views showing modified forms of fire-bars. Fig. 6 is a transverse section of the bar, showing the fire-bars in side elevation. Fig. 7 is a perspective of one of the fire-bars. Fig. 8 is a sectional view on the line x-x of Fig. 6.

In the drawings, 2 represents the longitudinal parallel webs or ribs of the grate-bar, connected at their ends by heads 3 and provided in their outer surfaces with a series of vertical grooves 4, extending to the top of the webs. Upon the webs 2, extending transversely thereof, I arrange a series of cross or fire bars 5, having at their ends depending integral lugs 6, that extend down over the outside surfaces of said web when the cross-bars are placed thereon. The inner faces of these lugs are beveled, forming knife-edges 7, which enter the grooves 4 in said web and retain the fire-bars in position thereon. The

knife-edges 7 preferably fit loosely within the grooves 4 in order that the unequal expansion and contraction of the webs and fire-bars will not cause any cracking or breaking of the same. Furthermore, the webs and bars, being cast separately, will not as readily transmit heat or cold from one to the other. At the lower edge of said fire-bars, upon each side, I prefer to arrange the lugs 8, having sharp upper edges 9 to deflect the ashes, the ends of said lugs abutting the ends of the lugs on the adjacent bars and keeping said bars separated and in their proper position on the webs, while permitting their ready removal.

In Fig. 4 I have shown a series of bars 9 arranged diagonally upon the webs, and in Fig. 5 I have shown V-shaped cross-bars, which, with the bars 9, are supported on the web in a manner corresponding to the bars above described.

Should one of the fire-bars become broken, it may be readily removed and a new one substituted, and as the parts are cast separately no coring will be required and the expense of manufacturing the bar greatly reduced.

Various ways may be devised for securing the fire-bars in position upon the web by any one skilled in the art, and I do not therefore wish to be confined to the details of construction above described.

Having thus described my invention, I claim as new and desire to secure by Letters Patent—

1. In a grate-bar, the combination, with substantially-parallel webs or bars, having slots in their outer faces, of fire-bars transversely arranged thereon, lugs provided on said fire-bars to enter said slots, and lugs provided between said bars and resting upon the tops of said webs, substantially as described.

2. In a grate-bar, the combination, with the webs 2 having the heads 3 and grooves 4, of the fire-bars 5 having lugs 6 to enter said grooves, lugs 8 provided on said bars and separating the same and the knife-edges 9 provided on said lugs 8, for the purpose specified.

3. In a grate-bar, the combination, with the parallel webs 2 and the heads 3 connect-

ing the same, of the fire-bars 5 transversely arranged upon said webs, each bar being disconnected from the other bars and having narrow elongated tops or surfaces whereto the fuel is laid, depending lugs 6 provided on said bars and adapted to extend down over said webs, lugs 8 provided on said bars and separating the same and adapted to rest upon

the tops of said webs, substantially as described.

In witness whereof I have hereunto set my hand this 16th day of January, 1900.

OTTIN OLSON.

In presence of—

RICHARD PAUL,
M. C. NOONAN.
